Application April 9, 1935, Serial No. 15,496
In Great Britain November 16, 1933

14 Claims. (CL 183—7)

This invention relates to the electrical treatment of fluids and, more particularly, it is directed to a method and apparatus for the electrical precipitation of suspended particles from gases.

5 A principal object of the invention is to improve the operation and increase the efficiency of the electrical precipitation of suspended particles from gases.

It has been found that by dividing the gas to be treated into a plurality of parallel streams, and passing each of said streams through separate treater units wherein the parallel streams are subjected to impulses of the same polarity derived from alternate successive half cycles of 10 a common source of alternating current, a number of highly important advantages may be attained.

Among these advantages are the following:

1. The amount of energy required to treat a given amount of gas is reduced.

20 2. Better operating characteristics are obtained in each of the parallel streams when they are subjected to impulses from alternate half cycles than when each stream is subjected to impulses from every half cycle of the current.

25 3. Poor operation in one of the parallel treater units, such as arcing over, is not reflected to the other units as is the case when all of the units are electrically connected in parallel.

30 4. The fact that electrical disturbances in one unit cannot be electrically reflected to another makes possible higher voltage and higher current input per impulse, both of which help to increase the efficiency of operation.

35 5. The electrical equipment required for energizing the precipitators is less when the method of the invention is used.

The invention provides method and apparatus embodying the foregoing advantages and characterized by applying every half cycle of a common source of alternating current successively and at constant polarity to a plurality of parallel streams of gas.

Within the limits just defined, the method and apparatus of the invention may be widely varied. The half cycles of the current source may be directed to the successive treater units at the same polarity by means of mechanical switching devices, by means of thermionic valves, or by means of combinations of mechanical and thermionic devices. Either the discharge or the collecting electrodes of the precipitator units may be grounded or both may be insulated from ground. The opposing electrodes may be brought to the same potential or to ground potential between

impulses, or they may be insulated from each other during the period between impulses. The electrical connections may be so arranged as to impress either the full available voltage or one half the available voltage across the electrodes 5 at each impulse. Other possible variations will be obvious to those skilled in the art from the following detailed description of various embodiments of the invention.

The invention will be more particularly described for the purpose of illustration with reference to the accompanying drawings in which:

Figs. 1-5 are schematic representations of electrical precipitation systems embodying the principles of the invention, wherein the full transformer voltage is impressed across the electrodes, the systems of Figs. 1, 3 and 4 utilizing mechanical energy directing devices, and the systems of Figs. 2 and 5 utilizing thermionic energy directing devices; and

Figs. 6-10 are schematic representations of electrical precipitation systems, in which half the full transformer voltage is impressed across the electrodes, the system of Fig. 6 utilizing thermionic energy directing devices, and the systems of Figs. 7-10 utilizing mechanical energy directing devices.

Figs. 3a, 4a, 9a and 9b are partial representations of the systems of Figs. 3, 4 and 9 respectively, showing modified forms of the systems of these figures.

In the figures A, B, C and D are precipitating chamber units comprising shells 1, which are grounded at 2 and in most of the embodiments illustrated also constitute collecting electrodes 3, and discharge electrodes 3, which are insulated by bushings from the collecting electrodes. The gases to be treated are supplied to the treating units in parallel streams from common headers 4. The electrical current supply is shown as 35 conductors 5 from a source of alternating current, connected to the primaries 6 of transformers T. The secondaries of the transformers are denoted by 7.

Referring more particularly to Fig. 1, the transformer T steps up the low voltage alternating current supply, for example, at 60 cycles per second and 440 volts (root mean square) to 60,000 volts (R. M. S.). The discharge electrodes 3 of precipitators A and B are connected permanently to 40 opposite terminals 8 and 9 of the secondary 7 of the transformer. Collecting electrodes 1 of A and B are alternately connected to the opposite terminals 8 and 9 through a common conductor 10 and the conductive shoes of a mechani- 55

cal rectifying switch S. Switch S, which is of the Lemp type and turns in synchronism with the source of alternating current (i. e. at 1800 R. P. M. for 60 cycle current), is similar to those commonly in use except that there is no need for four stationary shoes and only three are provided, designated by numerals 12, 13 and 14. The conducting strips 15 and 16 are mounted on insulating disc 17, which is mounted upon and rotated by shaft 18, and alternately connect first terminal 8 and then terminal 9 of the transformer to the collecting electrodes 1 and ground 2.

As shown in Fig. 1, strip 16 is connecting shoes 13 and 14 and grounding terminal 8 through conductor 10. When the switch is in this position, discharge electrode 3 of treater A, which is connected to 8 by conductor 18, is also grounded. In treater A, with these connections there is no potential difference between 1 and 3, no electrical field and corona discharge and no electrical energy being expended. Discharge electrode 3 of treater B, connected by 19 to terminal 9, is at the potential of 9. The opposing electrodes 1 and 3 of treater B are at this instant as far apart in voltage as are terminals 8 and 9 of the secondary winding 7 of the transformer and the electric field set up between them will effectively remove suspended particles from gases passing through the field. When shaft 18 turns 90 mechanical degrees in the direction indicated by the arrow, the voltage relationship in the transformer will have changed 180 electrical degrees, and terminal 9 will be at the same voltage but of opposite polarity with relation to the potential at 8. At this time, conducting strip 15 will be connecting stationary shoes 12 and 13 and will be grounding terminal 9 so that there will be no difference of potential between the electrodes of treater B. The opposing electrodes of treater A will now be at the potential difference of 8 and 9 and electrical precipitation will result therefrom in that unit.

The arrangement shown in Fig. 2 gives results similar to those obtained with the arrangement in Fig. 1, but in Fig. 2 two thermionic rectifiers V₁ and V₂ are used in place of the mechanical rectifier in Fig. 1. The anode of V₁ is connected to terminal 8 by conductor 23 and the anode of rectifier V₂ is connected to terminal 9 by conductor 24. The cathodes of both rectifiers are connected to the casings and the collecting electrodes of treater units A and B by conductor 10. In these treaters the side walls 1 function as collecting electrodes. Another wall 21 divides the unit into two parallel passages and this functions as a collecting electrode. Suspended vertically in the passages formed by 1 and 21 are discharge electrodes 3 connected in parallel by conductors 26 and 23 or 24 to terminal 8 or 9 of the transformer, respectively. The discharge electrodes 3 in A are permanently connected to 8, and those in B to 9. The collecting electrodes and flues are all conductively joined and are permanently connected to grounded conductor 10. Variable resistances R, R, are for the purpose of ballasting the electric circuits of which they are a part, and as they are adjustable, one resistance can be made to furnish greater impedance and voltage drop than the other, with the result that a lower voltage can be impressed across the complementary electrodes of one unit should the gas passing in that unit be more conductive than the gas passing in the other unit.

In operation, when the voltage of terminal 8 is positive with respect to conductor 10 and the

collecting electrodes connected thereto, current will easily pass through the rectifier V₁ connected to 8 and the potentials of 1, 21 and 3 in treater A will be substantially the same. No energy will be expended in A when this condition exists. The potential of terminal 9 is now negative with relation to 8 and to conductor 10, and as current cannot pass through rectifier V₂ when the anode is negative, the full voltage difference between terminals 8 and 9 is across that rectifier and consequently the same voltage difference is present between collecting electrodes 1, 21 and their complementary discharge electrodes 3 in unit B. In the next half cycle of the current supply, terminal 9 is positive and rectifier V₂ bypasses the current from the transformer around treater B. The complementary electrodes of treater A are now at full potential difference and the gas paths between them become part of the electric circuit.

With the hookups of Figs. 1 and 2, connections are established every other half cycle, by means of the mechanical switch 10 in Fig. 1 and by means of thermionic rectifiers 21 and 22 in Fig. 2, whereby the complementary electrodes of each unit are brought to equal potential every other half cycle, and during that half cycle, full transformer voltage is impressed across the complementary electrodes of the other unit. This set of conditions has been found to give good results in practice, but even better results may be secured in some installations by isolating the discharge electrodes of one unit during the half cycle that the discharge electrodes of the other unit are being charged. In other words, the potential of any discharge electrode is never allowed to drop to the potential of its complementary collecting electrode, even during the periods when it is bypassed or isolated from the unit undergoing energization. In the embodiment shown in Fig. 5, this isolation of the discharge electrodes of alternate units during alternate half cycles is brought about by thermionic rectifiers V₃ and V₄. Otherwise the electrical connections are the same as those shown in Fig. 2. As shown, rectifier V₃ permits current to flow readily from terminal 8 to discharge electrode 3 when 8 is negative with relation to 3, but when 8 is positive, rectifier V₃ acts as a closed electrical valve and the charge on 3 can only get away by leaking through the gas surrounding 3 to the collecting electrode. Spark gaps may be used in place of rectifiers V₃ and V₄ with satisfactory results, but the vacuum tube rectifiers, although much more expensive, seem to give smoother circuit conditions.

Figs. 3 and 4 show circuits in which the results obtained in the circuit of Fig. 5 can be obtained with mechanical switch rectifiers. All the switches shown are turned with four pole synchronous motors and rotate 90 mechanical degrees while the alternating current source changes through 180 electrical degrees. The two switches of any arrangement shown in these figures can, therefore, be rotated by the same motor if that is a convenient manner of operation. In Fig. 3, the switching is accomplished with two switches S₁ and S₂, each of which has two circumferentially positioned rotating conductors 31, 32, 33 and 34. If terminal 8 is positive and terminal 9 is negative when the switches are in the position shown in Fig. 3, the collecting electrodes of both units will be positive, discharge electrode 3 of unit B will be negative, and discharge electrode 3 of unit A will be isolated. Upon elec-

trode 3 of unit A will be the residual charge from the previous half cycle. It will be again energized during the next half cycle when terminal 8 is negative and conductors 31-34 have been rotated through 90 mechanical degrees. The collecting electrodes are always positive.

By adding to the system a shoe 35 grounded as shown in Fig. 3a, this system also will operate to bring the opposing electrodes to ground potential in alternate half cycles.

It is sometimes advisable to divide an electrical precipitator into more than two units or sections and to energize each unit independently of the others. Fig. 4 shows how this can be done by using the principles of the present invention. The four units A, B, C, D indicated are connected through three mechanical switches S₁, S₂, S₃ to the high voltage winding of a transformer. Rectifier S₁ causes the current in conductors 41 and 42 to be of a chosen polarity at all times. Rectifying switch S₂, making one complete revolution for every two complete cycles of the supply current, connects unit A to one of the half cycles and unit B to another half cycle during that period. Switch S₃ separately connects units C and D to the supply source during the other two half cycles during the two cycle period.

The addition to the system of shoes 43 and 44, connected to ground as shown in Fig. 4a, changes the system from one in which the discharge electrodes are isolated between charges to one in which the discharge electrodes are grounded between charges.

In the hookups shown in Figs. 6, 7 and 8, the collecting electrodes and the midpoint of the secondary winding of the transformer are permanently connected to ground. In these systems therefore the charge across the opposed electrodes of the treating unit is one half the full available voltage of the transformer.

In Fig. 6, thermionic rectifiers V₁ and V₂ permit the discharge electrode 3 of treater A to be charged when terminal 8 is negative and discharge electrode 3 of treater B to be charged when terminal 9 is negative, the discharge electrodes being isolated between charges.

In Fig. 7, the same effect is obtained with mechanical rotating switches.

In Fig. 8, rotating switches S₁ and S₂ alternately connect terminals 8 and 9 with the discharge electrodes 3 of the treater units in the order A, D, B, C, isolating the discharge electrode between charges.

In the hookup shown in Fig. 9, both the discharge electrodes 3 and the collecting electrodes 90 are insulated from the grounded treater shells 1. The collecting electrodes 90 of treaters A and B are permanently connected to terminals 8 and 9, respectively, of the transformer secondary. Switch S₁ alternately connects the midpoint of the secondary discharge electrode 3 of treater unit A and to discharge electrode 3 of treater unit B.

By the addition of shoe 11, connected to ground as shown in Fig. 9a, the discharge electrodes can be brought to ground potential between charges.

A similar result to that obtained by the hookup shown in Fig. 9, can be obtained by replacing switch S₁ by two thermionic valves as shown in Fig. 9b, having their filaments connected to the midpoint of the transformer and their plates connected, one to the discharge electrode of treater unit A and the other to the discharge electrode of treater unit B.

In Fig. 10 is shown a hookup in which the mid-

point of the secondary winding of the transformer and the collecting electrodes of the treater units are permanently connected to ground, while the discharge electrodes 3 of treater units A and B are alternately connected to terminals 8 and 9 of the secondary through synchronous switches S₂ and S₃, respectively. Between charges, the electrodes 3 of treater units A and B are connected to ground through synchronous switches S₁, S₂ and S₁, S₃, respectively.

It will be noted that in all of the embodiments of the invention shown or described, every successive half cycle is applied at the same polarity (in the same electrical direction) alternately to a plurality of parallel divided streams of the gas to be treated, so that each half cycle of current is effectively used to energize in the same direction one of a plurality of gas treating units carrying parallel streams of the gas under treatment.

This application is a continuation-in-part of my application Serial No. 647,823, filed December 17, 1932, now U. S. Patent No. 2,000,654.

I claim:—

1. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to at least one point on the high voltage winding of said transformer, and energy directing devices adapted intermittently to disconnect an electrode of successive treater units from the high voltage winding of the transformer in synchronism with the alternations of current, whereby the current is intermittently impressed across the complementary electrodes of the treater units so as to produce in each of said units when energized an electric field of the same polarity.

2. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to at least one point on the high voltage winding of said transformer, and thermionic rectifiers adapted intermittently to disconnect an electrode of successive treater units from the high voltage winding of the transformer in synchronism with the alternations of current, whereby the current is intermittently impressed across the complementary electrodes of the treater units so as to produce in each of said units when energized an electric field of the same polarity.

3. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high

- voltage terminal of the transformer; means connecting the opposed electrodes of said pairs in common to the midpoint of the high voltage winding of the transformer, and energy directing devices adapted intermittently to disconnect an electrode of successive treater units from the high voltage winding of the transformer in synchronism with the alternations of current, whereby the current is intermittently impressed across the complementary electrodes of the treater units so as to produce in each of said units when energized an electric field of the same polarity.
4. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to the midpoint of the high voltage winding of said transformer, and energy directing devices adapted intermittently to disconnect an electrode of successive treater units from the midpoint of the high voltage winding in synchronism with the alternations of current, whereby the current is intermittently impressed across the complementary electrodes of the treater units so as to produce in each of said units when energized an electric field of the same polarity.
5. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer; means connecting the opposed electrodes of said pairs in common to the midpoint of the high voltage winding of the transformer, and thermionic rectifiers adapted intermittently to disconnect an electrode of successive treater units from the high voltage winding of the transformer in synchronism with the alternations of current, whereby the current is intermittently impressed across the complementary electrodes of the treater units so as to produce in each of said units when energized an electric field of the same polarity.
6. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to the midpoint of the high voltage winding of said transformer, and energy directing devices adapted alternately to disconnect one and the other of said high voltage terminals from electrodes of successive treater units in synchronism with the alternations of current, whereby the current is intermittently impressed across the complementary electrodes of the treater units so as to produce in each of said units when energized an electric field of the same polarity.
6. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to the midpoint of the high voltage winding of said transformer, and thermionic rectifiers adapted alternately to disconnect one and the other of said high voltage terminals from electrodes of successive treater units in synchronism with the alternations of current, whereby the current is intermittently impressed across the complementary electrodes of the treater units so as to produce in each of said units when energized an electric field of the same polarity.
7. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to the midpoint of the high voltage winding of said transformer, and energy directing devices adapted intermittently to disconnect an electrode of successive treater units from the midpoint of the high voltage winding in synchronism with the alternations of current, whereby the current is intermittently impressed across the complementary electrodes of the treater units so as to produce in each of said units when energized an electric field of the same polarity.
8. Apparatus for treating gases comprising a plurality of treater units each of which comprises at least one pair of complementary electrodes, means for passing a gas to be treated through said treater units in parallel streams, a high voltage transformer having its low voltage winding connected to a source of alternating current, means connecting one electrode of each of said pairs of complementary electrodes to a high voltage terminal of the transformer, means connecting the opposed electrodes of said pairs in common to the midpoint of the high voltage winding of said transformer, and thermionic rectifiers adapted intermittently to disconnect an electrode of successive treater units from the midpoint of the high voltage winding in synchronism with the alternations of current, whereby the current is intermittently impressed across the complementary electrodes of the treater units so as to produce in each of said units when energized an electric field of the same polarity.
9. Apparatus for treating gases comprising two treater units each of which comprises at least one pair of complementary electrodes, means for passing a gas to be treated through said treater units in parallel streams, a high voltage transformer having its low voltage winding connected to a source of alternating current, means connecting an electrode of one treater unit to one terminal of the secondary winding of the transformer including a thermionic rectifier positioned to pass current from the secondary to the electrode when said terminal is negative, means connecting a corresponding electrode of the other treater unit to the other terminal of the secondary including a thermionic rectifier positioned to pass current from the secondary to the electrode when the latter terminal is negative, and means connecting the opposed electrodes of the treater units in common to the midpoint of the secondary winding of the transformer, whereby a charge of constant direction is intermittently impressed across the electrodes of said treater units in alternation.
10. Apparatus for treating gases comprising two treater units each of which comprises at least one pair of complementary electrodes, means for passing a gas to be treated through said treater units in parallel streams, a high voltage transformer having its low voltage winding connected to a source of alternating current, means connecting an electrode of one treater unit to one

terminal of the secondary winding of the transformer, means connecting the corresponding electrode of the other treater unit to the other terminal of the secondary, means connecting the 5 opposing electrodes of each of the treater units to the midpoint of the transformer, the last named connecting means including in the connection to each treater unit a thermionic rectifier positioned to pass current only in the direction 10 from the transformer to the electrode, whereby a charge of constant direction is intermittently impressed across the electrodes of said treater units in alternation.

11. A method of precipitating suspended particles from gases which comprises dividing the 15 gas to be treated into a plurality of parallel gas streams, passing each of said gas streams through a treater unit comprising at least one pair of opposed electrode members, and impressing successive 20 half cycles of a high potential alternating current in the same direction across opposed electrode members of each of said treater units in succession.

12. A method of precipitating suspended particles from gases which comprises dividing the 25 gas to be treated into a plurality of parallel gas streams, passing each of said gas streams through a treater unit comprising at least one pair of opposed electrode members, impressing successive 30 half cycles of a high potential alternating current in the same direction across opposed electrode members of each of said treater units in succession, and bringing the opposed electrodes

to the same potential during the interval between charges.

13. A method of precipitating suspended particles from gases which comprises dividing the gas to be treated into a plurality of parallel gas 5 streams, subjecting each of said parallel gas streams intermittently to the effect of a half cycle of a high potential alternating current in the same direction, and bringing the opposed electrodes to the same potential during the interval between charges. 10

14. Apparatus for treating gases comprising a plurality of treater units each of which comprises at least one pair of complementary electrodes, means for passing a gas to be treated 15 through said treater units in parallel streams, a high voltage transformer having its low voltage winding connected to a source of alternating current, circuit elements connecting one electrode of each of said pairs of complementary 20 electrodes to a high voltage terminal of the transformer, and circuit elements connecting the opposed electrodes of said pairs to at least one point on the high voltage winding, said circuit elements including energy-directing devices 25 adapted intermittently to break the conductive connection to one point on the high voltage winding of the transformer in synchronism with the alternations of current, whereby the current is intermittently impressed across the complementary electrodes of the treater units so as to produce in each of said units when energized an electric field of the same polarity. 30

HARRY A. WINTERMUTE.
